[57] CLAIM

The ornamental design for an artificial fishing lure, as shown and described.

DESCRIPTION

FIG. 1 is a side elevation view of an artificial fishing lure showing my new design, the opposite side being a mirror image of that shown;

FIG. 2 is a rear end view thereof;

FIG. 3 is a front end view thereof;

FIG. 4 is a top plan view thereof, the bottom view being a mirror image of that shown; and,

FIG. 5 is a side elevation view thereof shown in the condition of use, the broken lines being for illustrative purposes only and forming no part of the claimed design.
